CONVERSATION TIMING TRUNK CIRCUIT

Ernest H. Gatzert, Rochester, N. Y., assignor to General Dynamics Corporation, a corporation of Delaware

Application July 29, 1955, Serial No. 525,254

4 Claims. (Cl. 179—7.1)

This invention relates to trunk circuits equipped for conversation timing and more particularly to a method for connecting common timing apparatus to any one of a group of individual trunks.

It is the practice to provide connecting apparatus individual to each timed trunk circuit for extending a connection from a common timer circuit to control apparatus within each trunk circuit. The control apparatus is effective for causing the well known holding means within each trunk circuit to release an established connection set up through the trunk circuit and a train of switches a predetermined time interval after such a connection has been established. It is generally accepted practice to provide apparatus for applying a warning tone to such an established connection that is about to be released by the action of the timer. In such systems, it has been necessary to provide a group of relays associated with each of the trunk circuits equipped for conversation timing for the sole purpose of extending connections between the common timing apparatus and the individual trunk circuits as well as relays for such purposes as connecting the source of warning tone to the individual established connection.

Accordingly, it is an object of my invention to provide new and improved means for extending a connection between a common timer circuit and connection holding apparatus individual to each one of a group of trunk circuits.

I accomplish this and other objects by providing a telephone system comprising a switch train for establishing connections and means such as a trunk termination for controlling the switch train. Means associated with the connection establishing equipment is operative responsive to the seizure of the switch train for operating means for holding the switch train after a connection has been established. Common to a group of such holding means is a circuit for periodically producing spaced-apart timing signals. Responsive to the transmission of a supervisory signal, which marks the establishment of a connection and the beginning of a conversation, means comprising a two-step relay having a normal and first second operated positions is operative to its second position (i. e., through its second step) for maintaining the holding means in operated condition under the control of signals from the timing signal producing means. The timing signal producing means is thereafter operative in response to the operation of the two-step relay through its second step for releasing the relay to its normal position. The timing signal producing means is thereafter operative a predetermined time interval following the operation of the supervisory means for releasing the holding means in order to disable the established connection after the time-out period has elapsed. Another signal transmitted from the timing signal producing means is operative in response to the release of the relay during the time that the holding means is being maintained in operated condition for re-operating the relay to its first position (i. e., through its first step). Means comprising contacts on the relay

2

which are effective only in response to the operation of the relay through its first step are then effective for connecting a warning tone source to the termination to indicate to the connection that the cutoff is about to occur.

5 Further objects and advantages of my invention will become apparent as the following description proceeds, and the features of novelty which characterize it will be pointed out with particularity in the claims annexed to and forming a part of this specification.

10 For a better understanding of my invention, reference may be had to the accompanying drawings in which:

Fig. 1 is a skeletonized representation of apparatus found at the calling end of a trunk circuit;

Fig. 2 shows a representation in block form of an interrupter circuit;

Figs. 3-5 show a termination for an incoming trunk circuit;

Fig. 5 also shows skeletonized representations of an incoming selector, a connector, and a subscriber line; and

20 Fig. 6 shows a timing chart representing the output impulses of the timer circuit of Fig. 2.

The apparatus which forms the preferred embodiment of my invention is made to function from a source of power such as a battery. The most positive plate or terminal of this battery is connected to ground and is hereinafter referred to as "ground" and in the drawings as (+). The most negative, ungrounded terminal or plate of the battery is hereinafter referred to as "battery" and in the drawings as (-).

30 Referring to Fig. 1, a call may be originated by seizing an outgoing trunk such as the one comprising conductors T1 and R1 by the well known method of completing a short between the conductors by means such as dial contacts 101. The completion of the short is effective for

35 operating calling bridge relay 400 in the incoming trunk termination shown in Figs. 3-5 over the following loop: from ground, through the upper winding of relay 400, resistor R40, the upper lefthand winding of repeat coil RC40, break contacts 321, conductor T1, break contacts

40 101 of the dial, conductor R1, break contacts 323, the lower lefthand winding of repeat coil RC40, resistor R41, and the lower winding of relay 400 to battery.

The operation of relay 400 is effective for operating circuit holding means comprising release delay relay 500

45 within the trunk termination over the following path: from ground, through break contacts 307 and 315, make contacts 401, and the winding of relay 500 to battery. At this time the operation of relay 500 is effective to close a circuit for the lower biasing winding of the well known supervisory relay 320 through make contacts 502 and resistor R32, and for seizing the incoming selector IS500, which is of the well known step-by-step type, by closing a loop circuit for selector IS500 comprising conductor T4,

50 the upper righthand winding of repeat coil RC40, the upper winding of supervisory relay 320, resistor R31, the lower righthand winding of repeat coil RC40, break contacts 431, make contacts 501, and conductor R4. Relay 320 is unoperated because the current flowing through the upper winding from the succeeding switch train is in such

55 a direction that it causes flux in the magnetic circuit of relay 320 that is opposed to the flux caused by current flowing through the lower biasing winding of the same relay. The contacts 501 are thereafter effective for maintaining the loop in order to hold the switch train including selector IS500 and connector C500. The holding process is described in more detail in the following paragraphs.

60 Incoming selector IS500 is next driven to the required level and advanced within that level to seize a connector circuit such as C500. Connector C500 is then advanced in its primary and secondary directions in order to seize a subscriber line such as A. The process of advancing selec-

tor IS500 and thereafter connector C500 is carried out in the well known manner in response to the repetition of trains of impulses by relay 400 when the latter repeats impulses caused by the opening and closing of dial contacts 101. Impulse repeating contacts 402 in relay 400 drive well known pulse correcting means comprising pulse correction 1 and pulse correction 2 relays, 420 and 430 respectively, in the trunk termination. Relays 420 and 430 are thereupon effective in the well known manner in response to the operation of impulses repeating contacts 402 for repeating trains of corrected impulses to the succeeding switch train by opening and closing the previously traced loop comprising conductors T4 and R4 at break contacts 431. Such impulses drive selector IS500 and thereafter connector C500 in a manner well understood by those skilled in the telephone art. Because the advance of the switch train does not form a part of the present invention, a detailed description of the process is not considered to be necessary.

After a connection has been extended to station A, the connection is completed by the answering of the telephone at station A. Thereupon, means such as hookswitch contact H501 at station A are closed in order to send back a supervisory signal into connector C500 to operate supervisory relay 510. The operation of relay 510 causes a signal to be transmitted from connector C500 to the incoming trunk termination in the form of a reversal in the direction of current flow through the previously described loop comprising conductors T4 and R4 and the upper winding of supervisory relay 320. The reversal is caused by the opening of break contacts 511 and 513 and the closing of make contacts 512 and 514. The reversal of current flowing through the upper winding of relay 320 is effective for altering the magnetic field of that relay so that the flux created by current flowing in the upper and lower windings is additive and therefore sufficient to cause relay 320 to operate.

The operation of relay 320 is effective for reversing the direction of current flow in the trunk conductors T1 and R1 in the well known manner to signal an off-hook condition at station A to the apparatus in Fig. 1. The operation of relay 320 is also effective at this time for starting the timing process by transferring the winding of release delay relay 500 from its above described connection which was completed by the operation of the seizure responsive relay 400 to means controlled by the cyclically operating timing impulses generating means shown in the block representation of Fig. 2. The timing process is next described.

The timing impulse generating means may be of the rotary type. Because such apparatus is well known and understood by those skilled in the telephone art, a detailed description of its operation here is not considered to be necessary to the understanding of the present invention. Referring to Fig. 6, upon the start of the cycle of operations of the timing impulse producing means of Fig. 2, a timing start signal comprising a ground impulse is placed on conductor TP1 and is effective for completing an operating circuit for the two-step timer-connector 1 relay 310. This circuit is traced as follows: from conductor TP1, through break contacts 301, make contacts 326, break contacts 312, and the upper winding of relay 310 to battery. The operation of relay 310 is effective for establishing a holding circuit for relay 310 which is traced as follows: from ground, through make contacts 502, break contacts 303, make contacts 311, and the upper winding of relay 310 to battery. Thus it is seen that relay 310 is held in operated condition from ground supplied through the contacts of release delay relay 500 at this time. The operation of relay 310 is also effective for transferring the energizing circuit for release delay relay 500 from the previously traced ground source which included break contacts 315 and 307 to a direct ground source by closing make contacts 316 and opening break contacts 315.

After the timer, shown in Fig. 2, has completed a first cycle of operations a ground impulse is placed on conductor TP2. The placing of the ground impulse on conductor TP2 is effective for completing an operating circuit for the remainder of the timer connecting means, namely, timer-connector 2 relay 300. The circuit is traced as follows: from conductor TP2, through now closed make contacts 314, break contacts 306, and the winding of relay 300 to battery. Relay 300 thereupon operates and closes the following locking circuit for itself: from ground, through make contacts 503, make contacts 305, and the winding of relay 300 to battery. The operation of relay 300 is also effective to transfer the upper winding of relay 310 from its previously traced holding circuit which included break contacts 303 to a holding circuit comprising conductor H1. It is to be noted in Fig. 6 that at the time that relay 300 is operated in response to the impulse on conductor TP2, the timing impulse producing means has placed ground on conductor H1. Owing to the make-before-break nature of contacts 302 and 303, the transfer of the holding circuit for the upper winding of relay 310 is accomplished without interruption so that relay 310 is held operated steadily during the operation of relay 300.

The timing impulse connecting means comprising relays 300 and 310 remain in this condition until the appearance of a first absence of ground signal on conductor H1 which occurs toward the end of the cycle of operations of the timing impulse producing means. The absence of ground on conductor H1 is of sufficient duration to allow relay 310 to be released. The release of relay 310 is effective for transferring the previously described holding circuit for relay 500 which included operated make contacts 316 on relay 310 to a holding ground supplied as a second signal from timing pulse producing means over conductor H2. The latter circuit is traced as follows: from conductor H2, through make contacts 308, break contacts 315, make contacts 401, and the winding of relay 500 to battery. Thus, relay 500 is thereafter maintained in its operated condition so long as the ground is held on conductor H2. It is to be noted in Fig. 6 that at the time that ground is removed from the H1 conductor, ground is present on the H2 conductor and continues to be present until the completion of the current as well as the next succeeding cycle of operations of the timing impulse producing means.

Assume that the above described connection from Fig. 1 through selector IS500 and connector C500 to station A is held for an interval greater than the maximum timed interval. In the preferred embodiment of my invention such a time interval is measured by three full cycles of operations of the impulse producing means shown in Fig. 2. During the last of these cycles of operations, the above described operation of relay 300 and the release of relay 310 is effective for completing a circuit comprising break contacts 313 and 304 for extending a connection from conversation warning tone conductor CWT to the upper winding of relay 310 upon the appearance of a third signal comprising a ground impulse on lead CWT during the third (last) of the cycles of operations of the timing impulse producing means. The circuit is traced as follows: from conductor CWT, through make contacts 304, break contacts 313, resistor R30, and the upper winding of relay 310 to battery. Resistor R30 limits the current flowing within the upper winding of relays 310 to a point that is sufficient to operate the two step relay through its first step only. Accordingly, only the preliminary contacts such as 318 on relay 310 are operated at this time. All other contacts remain in their normal, released condition. Accordingly, the operation of relay 300 and the operation of relay 310 through its first step completes a circuit from the tone source comprising generator GR30 which is traced as follows: from ground, through generator GR30, blocking condenser C30, now operated make contacts 309 and 318, break

contacts 317, the lower lefthand winding of repeat coil RC40, and the resistance-capacitance network comprising capacitor C31 and resistors R49 and R41 to ground through the windings of calling bridge relay 400. The application of the potential is sufficient to cause a tone to be heard at stations such as A which are a part of the above described connection and warn the subscriber using the station that the conversation is about to be cut off.

From Fig. 6 it is seen that at the end of the third cycle of operations of the timing impulse producing means (following the removal of the ground impulse from conductor CWT and the resulting re-release of relay 310), ground is removed from conductor H2. The absence of ground signal on conductor H2 opens the last traced holding circuit for release delay relay 500. Relay 500 thereupon releases.

The release of the holding means comprising relay 500 is effective for opening the seizing and holding loop circuit at make contacts 501. The switches in the connection, such as IS500 and C500, are thereupon restored in the well known manner to their normal conditions to break the previously traced connection established through the switch train a predetermined time interval following the transmission of off-hook supervision from station A to the trunk termination.

In the event that a call is routed through the switching means comprising incoming selector IS500 to a destination, such as an outgoing trunk OGT, it may be desirable to cancel the above described operation of the conversation timing facilities. Such trunks are usually located within a particular level to which the selector has access. In order to provide a signal for causing the cancellation of the timing facilities, well known level marking means within selector IS500 comprising a wiper, such as S51, is advanced one step over a bank of conductors for each primary step taken by the switch wiper, shown collectively as S59. A more detailed description of such level marking means may be found in Patent 2,669,606, issued February 16, 1954, to Frank Kessler et al. and assigned to the present assignee of record. In the preferred embodiment of my invention, such outgoing trunks are shown connected in the sixth level. Thus, when wiper S51 is advanced to the sixth successive contact, a signal is transmitted over the following circuit for operating timer-connector relay 310: from ground, through wiper S51, conductor LM, and the lower winding of relay 310 to battery. Relay 310 thereupon operates and remains operated throughout the duration of the call. The subsequent operation of relay 300 and the transfer of the upper winding from the holding ground to the conductor H1 in the previously described manner is now ineffective to bring about the release of relay 310 in the previously described manner. Under these conditions relay 500 is held operated under the control of make contacts 401 on calling bridge relay 400 from ground supplied through make contacts 316. The timing impulse producing means is therefore not effective for causing the release of the holding means comprising relay 500 and calls extended through the sixth level of selector IS500.

While I have shown and described a specific embodiment of my invention, other modifications will readily occur to those skilled in the art. I do not, therefore, desire my invention to be limited to the specific arrangement shown and described, and I intend in the appended claims to cover all modifications within the spirit and scope of my invention.

What is claimed is:

1. In a telephone system, means comprising a switch train for establishing a connection, means for seizing and thereafter controlling the advance of said train, means for holding said train, means operative in response to the operation of said seizing means for operating said holding means, means for periodically producing timing signals,

means for transmitting supervisory signals over a connection established over said switch train, means for repeating supervisory signals, means comprising a relay having a normal position and first and second operated positions operative to its second position in response to the operation of said supervisory means for thereafter maintaining said holding means operated under the control of said timing signal producing means, said timing signal producing means being operative for releasing said relay to its normal position and thereafter operative in response to the release of said relay a predetermined interval of time following the operation of said supervisory means for releasing said holding means, means utilizing another signal from said timing signal producing means and effective in response to the release of said relay prior to the release of said holding means for operating said relay to its first position, a tone source, and means operative in response to the operation of said relay to its first position for connecting said tone source to a connection established over said switch train.

2. The system set forth in claim 1 and having in addition means operative in response to the establishment of a connection through said switch train over a particular route for operating said relay to its second position, whereby the release of said holding means by said timing means is prevented.

3. In a telephone system, means comprising a switch train for establishing a connection, a trunk termination circuit for seizing and thereafter controlling the advance of said switch in said train, means for holding said switch train, a circuit for operating said holding means, means operative in response to the seizure of said termination for completing said circuit over a first path, means for periodically producing a plurality of timing signals, means for transmitting supervisory signals over a connection established over said switch train, means for repeating supervisory signals, means comprising a relay having a normal position and first and second operated positions operative to its second position in response to the operation of said supervisory means and to the transmission of a start signal from said timing signal producing means for rendering said seizure responsive means inoperative with respect to said holding circuit and for thereupon causing said holding circuit to be completed over a different path, means operative in response to the operation of said relay to its second position and to the subsequent transmission of a first signal from said timing signal producing means for releasing said relay to its normal position and thereafter operative in response to the release of said relay for causing said holding means to be operated by a second signal transmitted from said signal generating means, means operative in response to the release of said relay and to the subsequent transmission of a third signal from said timing signal producing means for operating said relay to its first position, a tone source, and means operative in response to the operation of said relay to its first position for connecting said tone source to said connection.

4. The system set forth in claim 3 and having in addition means operative in response to the establishment of a connection through said switch train over a particular route for operating said relay to its second position and for thereafter maintaining said relay operated in its second position, whereby the release of said holding means by said timing means is prevented.
